R. B. BENJAMIN

ATTACHMENT PLUG

Filed Oct. 30, 1919

Inventor
Reuben B. Benjamin

Jones, Addington, Ames, Seibold
Attorneys

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT PLUG.

Application filed October 30, 1919. Serial No. 334,476.

To all whom it may concern:

Be it known that I, REUBEN B. BENJAMIN, a citizen of the United States, residing at Chicago, in the county of Cook and State 5 of Illinois, have invented new and useful Improvements in Attachment Plugs, of which the following is a full, clear, concise, and exact description, reference being had to the accompanying drawing, forming a 10 part of this specification.

My invention pertains to attachment plugs, and has as one of its objects, the provision of a plug of a simple and durable construction, which may be placed upon the 15 market at a low price.

It is another object of my invention to provide a simplified form of plug having conductor gripping means for relieving the binding terminal from strain.

20 A plug constructed in accordance with my invention is described, by way of example, in the following specification and shown in the accompanying drawing. It is to be understood, however, that changes 25 may be made in the embodiment of my invention which I have chosen to describe and show, without exceeding the scope of the invention, as defined in the appended claims.

In the drawing:

30 Fig. 1 is a vertical section taken through a plug constructed in accordance with my invention, the section being taken on the line 1—1 of Fig. 4, looking in the direction of the arrows;

35 Fig. 2 is a view similar to Fig. 1, the section being, however, taken on the line 2—2 of Fig. 4, looking in the direction of the arrows;

40 Fig. 3 is a view similar to Fig. 1, the section being, however, taken on the line 3—3 of Fig. 4, looking in the direction of the arrows;

Fig. 4 is a plan view of the plug;

45 Fig. 5 is an inverted plan view of the insulating base which carries the contacts;

Fig. 6 is a plan view of the insulating ring which serves as a hand-hold;

50 Fig. 7 is a detail perspective view of the insulating base which carries the contacts, and

Fig. 8 is a detail perspective view of the threaded shell contact.

Like reference characters refer to like parts throughout the specification and the several figures of the accompanying drawing.

Referring now to the drawing, 10 designates an insulating base having, at its upper end, a reduced end 11. Secured to the base 10 is a threaded shell contact 12, the lower end of which is flanged over at 13, so as to engage against the bottom of the base 10. The upper end of the shell is provided with an inwardly extending flange 14 which engages the shoulder at the point where the 65 extension 11 projects from the base 10. The base 10 is provided with a recess 15 underneath the flange 14 in which recess is located a nut 16, such nut receiving the binding screw 17 which extends through an 70 opening 17^a in the flange 14, and is threaded into the nut 16. The base 10 is formed with a conductor-receiving passage 18 which extends therethrough between the axis and the periphery of the base, the upper end of this 75 passage opening near the binding screw 17, and registering with an opening 18^a in the flange 14, so as to permit the conductor readily to be brought into position for securing thereunder. In order to further position the threaded shell contact 12 on the insulating base 10, the flange 14 of the threaded shell contact is provided with an inwardly extending projection 18^b which registers with a corresponding depression 80 85 18^c in the insulating base.

A screw 19 passes longitudinally through the base 10, such being provided with a washer 20 having a horizontal flange 21 which lies flush with the head of the screw 90 19, resting upon the top of the extension 11. The base extension 11 is formed with a chamber 22 which receives the lower parts of the washer 20 and the head of the screw 19. A conductor-receiving passage 23 is 95 formed in the base 10 between the axis and the periphery thereof, such passage being disposed diametrically opposite to the passage 18. The passage 23 opens into the chamber 22, and permits a conductor to be led into the chamber 22 and secured therein beneath the washer 20. The head of the screw 19, together with the washer-flange 21, forms the center contact of the plug.

The screw 19 is threaded into an upwardly-extending stirrup 24 having downwardly-extending legs 25, which are imbedded in an insulating ring 26, which may be formed of hard rubber or the like. The stirrup 24 enters a correspondingly shaped recess 27 formed in the base 10. When the screw 19 is screwed into the stirrup 24, it firmly draws the ring 26 against the lower side of the base 10, thus securing the parts of the plug firmly together. By reason of the engagement of the stirrup 24 in the recess 27, relative rotation between the ring 26 and the base 10 is effectually prevented. The ring 26 is formed with a central aperture 28 through which the conductors may be passed to the binding terminals of the plug. At the top edge of the aperture 28, the ring 26 is formed with two small channels 29 and 30, facing the passages 18 and 23 respectively, so as to facilitate the leading of the conductors from the aperture 28 into the passages 18 and 23.

In connecting up the plug for use, the ring 26 is separated from the base 10 by loosening the screw 19. The conductors are passed through the aperture 28 of the ring 26, and one of them is led through the passage 18 and secured beneath the binding screw 17, the other conductor being led through the passage 23 and placed in position beneath the washer 20. The stirrup 24 is then inserted into the recess 27 and the screw 19 tightened down. The effect of tightening the screw 19 is to clamp the conductor firmly beneath the washer 20, and also to draw the ring 26 toward the lower side of the base 10. The result of drawing the ring 26 toward the lower side of the base 10 is that the conductors are firmly clamped between the ring and the base, and the binding terminal thereby being effectively relieved from strain.

The construction of the plug described above is such that it may be placed upon the market at a small cost, whilst, at the same time, the conducting parts of the plug are efficiently insulated from each other and the binding terminals are effectively guarded against the strain being applied thereto.

It will be noted that the threaded shell contact 12 will be held in place permanently on the insulating base 10, when the base 10 is separated from the insulating ring or thumb piece 26, making the plug easy to assemble and wire, as there is no danger of the shell contact falling off.

This application is a continuation as to common subject claimed herein of my pending application Serial No. 766,557, filed May 9, 1913; renewed Sept. 20, 1918, Serial No. 255,013.

Having thus described my invention,

what I claim as new and desire to secure by Letters Patent of the United States is:

1. An attachment plug comprising an insulating portion having a non-circular recess in the lower side thereof, a shell-contact associated with said insulating portion, a center contact including a screw disposed longitudinally of said insulating portion, and extending therethrough, and a second insulating portion having a metallic member secured thereto for receiving said screw, said member corresponding in shape to said recess and entering the latter and engaging the walls thereof.

2. An attachment plug comprising a shell contact, a center contact including a screw, an insulating portion receiving said contacts and formed with conductor-receiving passages, said insulating portion having a non-circular recess in the lower side thereof, a second insulating portion having an aperture therethrough for receiving the conductors, said aperture being disposed so that its edge grips the conductors contained in said passages, a metallic member secured to said second named insulating portion, for receiving said screw, said member corresponding in shape to said recess and entering the latter and engaging the walls thereof.

3. An attachment plug comprising a shell contact, a center contact including a screw, an insulating portion receiving said contacts and formed with conductor-receiving passages, said insulating portion having a non-circular recess in the lower side thereof, a second insulating portion having an aperture therethrough for receiving the conductors, said aperture being disposed so that its edge grips the conductors contained in said passages, and a metallic strap for receiving said screw, extending upward from said second named insulating portion and straddling said aperture, said strap corresponding in shape to said recess and entering the latter and engaging the walls thereof.

4. An attachment plug comprising an insulating portion having a pair of binding posts thereon, a pair of conductor-receiving passages therein, offset from the axis thereof, and leading from said binding posts, a second insulating portion having an axial conductor-receiving opening therethrough, said opening communicating with both of said passages, the edge of said opening being adjacent the inner edges of said passages, and means for drawing said portions together to clamp the conductors between said edges.

In witness whereof, I have hereunto subscribed my name.

REUBEN B. BENJAMIN.
